The ornamental design for a lounge chair, as shown and described.

DESCRIPTION

FIG. 1 is a perspective view of a lounge chair, looking toward the right front corner, showing my new design;
FIG. 2 is a front view thereof;
FIG. 3 is a right side view, the left side view being a mirror image thereof;

FIG. 4 is a back view thereof;

FIG. 5 is a top view thereof; and,

FIG. 6 is a bottom view thereof.

The broken lines shown in the drawing are for illustrative purposes only and form no part of the claimed design.
